CRANE

Original Filed Feb. 6, 1945

UNITED STATES PATENT OFFICE

2,553,955

CRANE

Wallace W. Berchtold, York, Pa., assignor to
American Chain & Cable Company, Inc.,
Bridgeport, Conn., a corporation of New York

Original application February 6, 1945, Serial No.
576,414. Divided and this application January
3, 1947, Serial No. 720,118

2 Claims. (Cl. 212—8)

1

This application is a division of my co-pending application 576,414, filed February 6, 1945, now Patent No. 2,419,813, granted April 29, 1947, for a Crane.

The invention relates to a crane having general application but constructed particularly for garage use, such as for the removal of the engine or motor of cars and especially for the removal of the motor from the rear end of a bus.

It is an object of the invention to construct a crane having general utility and also particularly suited for removing the rear end mounted motor of a bus.

Another object of the invention is to construct a new and novel portable crane having a plurality of crane arms.

Another object is to construct a crane having a general utility arm and an additional arm or boom particularly suited for removal of the rear end mounted motor of a bus.

Other objects of the invention will be more apparent from the following description taken in connection with the accompanying drawings illustrating the preferred embodiment thereof in which:

Figure 1 is a side elevation of the crane using two arms for the removal of a bus motor shown diagrammatically in dot-dash lines.

Figure 2 is a top view of the crane.

Because of the limitations of space in the location of the motor at the rear end of a bus, it is difficult to remove the same therefrom. Such motors are heavy and require the use of a crane for their removal. The crane herein is provided with a plurality of arms, one of which may be used for general lifting purposes and the pair of arms are used particularly for the removal of the motor of the bus in the confined space in which said motors are mounted.

The crane provides a frame of any suitable form, that illustrated including a U or horse-shoe shaped lower frame 10 provided with a cross bar 11. A vertical standard 12 is carried by the cross bar. The vertical standard is braced by means of bars 13 extending from the top of the standard on each side thereof and to the U-shaped frame. A brace 14 also extends rearwardly from the standard to the rear of the U-shaped frame. One of the braces 13 may carry rods 15 at spaced intervals to form a ladder. The frame may have swivel wheels 16 on the ends of the U-shaped lower frame and a wheel 16 at the bend in the U. This construction of U-shaped frame permits the load to be straddled by the arms of the U for ease in attaching the

2

hoist hook and in lifting a load whereupon the crane and load may be moved away.

A bracket 17 at the top of the vertical standard carries a slide 19 which receives an arm 20 slideable therein so that the arm may be extended or retracted as desired. Any suitable means may be used to lock the arm in its adjusted position, the means particularly illustrated including a series of holes 21 which receive a lock pin 22 carried by the slide.

The hoisting means may take any desired form, that illustrated being a manual hoist carried by the frame and slideable arm. The hoisting means includes a drum, which may be in a housing 24, carrying a cable 25 which drum is rotated by a handle 26 preferably connected by a self-locking worm to the drum shaft 27. The drum and its mechanism is mounted upon the brace 14. The cable extends over a pulley 28 mounted upon the bracket 17 and then over a pulley 29 carried upon the end of the adjustable arm 20, the cable connecting with a snatch block 30. The snatch block carries a hook 31 for supporting a load directly from the arm 20 or for attachment to a secondary arm.

The crane is provided with a plurality of arms, which includes the adjustable arm 20 and a boom or secondary arm 35 which is swingable vertically on a pivot 36 carried by a bracket 37. This bracket is mounted upon the standard 12 and preferably is slideable thereupon for adjusting its vertical position. The adjustment mechanism includes a plurality of holes 38 in the standard which receive a lock pin 39 carried by the bracket 37 to support the boom in adjusted position or elevation. The boom carries an attaching bracket 40 to receive the hook 31 of the snatch block 30 which bracket may be adjustable along the length of the boom. Three adjustment positions are shown represented by the holes 41 located along the length of the boom which holes receive a locking pin 42 carried by the attaching bracket. The boom may carry a hook 43 shown at the outer end thereof to carry the load supported by the boom. The pivot 36 not only permits the boom to swing vertically but enables it to swing downwardly out of the way when not in use either in front of the standard as shown in dotted lines in Figure 1 or it may be rotated and hang out of the way on the other side of the standard.

The boom 35 may be adjusted in its elevation or vertical position so that it can project into the limited space above the motor in the motor hood at the rear end of the bus whereupon the

motor is secured to the hook 43 such as by cables or other means and lifted off of its supporting structure by the hoisting means. The crane may then be moved to withdraw the engine from the bus. The adjustment of the boom enables it to be fixed at the proper elevation for whatever job it is intended to perform in some confined space. The adjustable position for the attaching bracket 46 permits variation of the leverage applied to the boom and also permits the boom to extend into the bus hood without interference with the snatch block. When the boom is in use the upper arm 20 may be slid to any one of its retracted positions, Figure 3 showing the arm retracted substantially its full length.

This invention is presented to fill a need for improvements in a crane. It is understood that various modifications in structure, as well as changes in mode of operation, assembly, and manner of use, may and often do occur to those skilled in the art, especially after benefitting from the teachings of an invention. Hence, it will be understood that this disclosure is illustrative of preferred means of embodying the invention in useful form by explaining the construction, operation and advantages thereof.

I claim:

1. A crane comprising a U-shaped frame, a cross bar adjacent the closed end of the frame, a vertical standard carried by the cross bar, braces extending from the top of the standard to the U-shaped frame, an arm carried by the upper end of the standard for projection there-

from by different amounts, hoisting means mounted upon one of the braces and on the arm, a secondary arm mounted on the standard for vertical pivotal movement, said hoisting means being connected thereto, and said arm having load carrying means on the end thereof.

2. A crane comprising a frame including a vertical standard, a slide carried by the upper end of the frame, an arm carried by the slide and adjustable horizontally with respect to the standard, hoisting means carried by the frame and arm, a bracket carried by the standard intermediate the ends thereof, a boom pivotally carried by the bracket for movement in a vertical plane, means carried by the boom for connection with the hoisting means, and means upon the end of the boom for supporting a load.

WALLACE W. BERICHTOLD.
